(57) **CLAIM**

The ornamental design for a building, as shown and described.

DESCRIPTION

FIG. 1 is a perspective view of a building including a set of dwellings supported by a scaffold, the perspective view partially from the front of the set of dwellings, partially from the right side of the set of dwellings, and partially from the top of the set of dwellings;

FIG. 2 is a front view of the building of FIG. 1;

FIG. 3 is a back view of the building of FIG. 1;

FIG. 4 is a left side view of the building of FIG. 1;

FIG. 5 is a right side view of the building of FIG. 1, and shows a section line denoted 'A' ("Section A") demonstrating the cross sectional location of FIGS. 6; and, FIG. 6 is a top view of the building of FIG. 1, the top view beginning at Section A.

The broken lines in the embodiments of FIG. 1 through FIG. 6 depict portions of the building that form no part of the claimed design.

1 Claim, 6 Drawing Sheets
